CLOTHES POUNDER

Ernst Eberhard, Zurich, Switzerland

Application November 21, 1934, Serial No. 754,154
In Switzerland November 28, 1933

2 Claims. (Cl. 68—5)

The invention relates to a new and improved clothes pounder. The main object of the invention is to provide a simple and unexpensive device by means of which the water, soap suds, lye or liquor in a washing tub may be thoroughly circulated and the dirt from the clothes quickly and easily eliminated.

A further object of the invention consists in the provision of means to create alternately a 10 pounding action upon the clothes and a suction action thereon in order that air may be forced into and through the clothes and the liquor may be sucked therethrough.

I attain these and other objects by a cup-shaped plunger having at least one disk-valve operated by a bell-like body for controlling the inlet of the air and the suction of the water through the clothes while working the clothes pounder up and down, ensuring thereby a constant and active circulation of the water through the clothes.

In the accompanying drawing two preferred modes of construction are shown by way of examples. In the drawing:

20 Fig. 1 is a side elevation of a clothes pounder,
Fig. 2 is a bottom view of the pounder,
Fig. 3 is a longitudinal sectional elevation of the pounder,

25 Fig. 4 illustrates a modified construction of the pounder in a vertical longitudinal sectional view.

Referring more particularly to the drawing, 1 designates a rod or stem which may consist of one or of several parts removably interconnected. To the rod 1 a funnel shaped plunger 2 of sheet metal is attached. In the plunger 2 a horizontal shelf or partition wall 3 protruding inwardly is fixed, the said wall 3 having a circular central opening. A circular groove is provided in the wall 3 in which a ring of rubber or 35 the like is arranged. On the ring 4 rests a bell-shaped body 6 by means of a horizontal flange 5. A coiled spring 9 placed above body 6 within the funnel 3 tends to press the body 6 against the ring 4; the parts 4, 5 and 6 forming a disk-valve. The lower edge 7 of the body 6 projects below the lower edge 8 of the plunger 2. In the body 6 a perforated plate 10 is fixed. The plunger 2 is provided with a row of holes 11, arranged above the partition wall 3 and the body 6 with several rows of holes 12 below the plate 10.

In use the clothes-pounder is moved up and down in a wash tub containing clothes and soap-suds. By driving it downwards on to the clothes the bell-shaped body 6 striking against the clothes 50 is moved upwards against the action of spring 9. The air within the body 6 is forced out by the inflowing water, the air escapes by the holes

11 and 12, and passes into the water and into and through the clothes. The valve 4, 5 is open, water enters the plunger 2 and fills the same at least partly. The water escapes through the holes 11. If now the clothes pounder is lifted, the valve 4, 5 is closed by the action of the spring 9. A sucking and pulling action is now exerted by the rising clothes pounder, the clothes are partly lifted, water passes through the clothes, a constant and active circulation of the hot suds is 10 ensured.

The clothes-pounder shown in Fig. 4 differs from that described with reference to Figs. 1 to 3, in that the perforated partition wall 10 is arranged below the row of holes 12 in the bell 6. 15 The holes 15 of plate 10 are closed by a plate 14 resting loosely on the plate 10.

The action of this device is very similar to that described above. The air within the bell 6 is put under considerable pressure while the clothes- 20 pounder is driven on the clothes and is forced under pressure through the clothes.

I wish it clearly understood that I do not limit my invention to the particular device as shown and described but what I wish to secure by U. S. 20 Letters Patent is:—

1. In a clothes pounder, a hollow plunger, a horizontal shelf extending inwardly from the plunger wall and formed with a central opening, said plunger having openings above said shelf, 25 a movably mounted bell having a part thereof projecting through said opening and having an exterior horizontal flange adapted to rest on said shelf and having its lower edge normally projecting below the edge of said plunger, means urging 30 said flange against said shelf, said bell having openings which communicate with the openings in the plunger when the flange is moved away from the shelf, and means for operating said plunger and bell. 35

2. In a clothes pounder, a hollow plunger, a horizontal shelf extending inwardly from the plunger wall and formed with a central opening, said plunger having openings above said shelf, a movably mounted bell having a part thereof projecting through said opening and having an exterior horizontal flange adapted to rest on said shelf and having its lower edge normally projecting below the edge of said plunger, means urging 40 said flange against said shelf, a sealing means between the shelf of the plunger and the flange of the bell, said bell having openings which communicate with the openings in the plunger when the flange is moved away from the shelf, and means for operating said plunger and bell. 45

ERNST EBERHARD.
